UNITED STATES PATENT OFFICE.

JACOB WERSHOW, OF NEW HAVEN, CONNECTICUT.

PREPARATIONS OF MEDICINAL SUBSTANCES AND METHOD OF MAKING THE SAME.

1,404,673.

Specification of Letters Patent. Patented Jan. 24, 1922.

No Drawing.

Application filed February 11, 1921. Serial No. 444,278.

To all whom it may concern:

Be it known that I, JACOB WERSHOW, a citizen of the United States, and resident of New Haven, in the county of New Haven and State of Connecticut, have invented certain new and useful Improvements in Preparations of Medicinal Substances and Methods of Making the Same, of which the following is a specification.

10 My present invention relates more particularly to preparations of aspirin and the primary object is to embody characteristic medicinal properties of aspirin, in non-solid form, preferably in the form of a relatively 15 fluid or nonviscous liquid.

At the present time the medicinal properties of aspirin are well known and its commercial production and use in relatively enormous quantities has been practically 20 standardized in the form of so-called aspirin tablets. The aspirin employed is the acid form known as acetyl-salicylic acid, formula,

25 This substance is a crystalline solid and the tablets comprise the pulverized aspirin combined and compressed with a suitable binder and filler material. This standardized commercial practice has resulted from the fact 30 that the acid aspirin is insoluble, or practically insoluble in all ordinary liquids of the kinds which are suitable for use without themselves producing destructive or 35 harmful chemical or medicinal effects when taken internally. These aspirin tablets, however, are objectionable because, on account of their size and dryness, swallowing them whole is difficult and for some people 40 impossible; also because the filling and binding material or materials are apt to have more or less objectionable physiological effects, particularly in cases where the stomach is in a sensitive or disturbed condition; 45 also because the time required for the solid aspirin to be completely freed from the binder and to be released in the system in active medicinal form, is appreciable and may be objectionably long.

50 My invention in its more specific embodiments involves obviating all of these objections by embodying the active medicinal principles of the aspirin in a liquid which can be easily and even pleasurable swallowed 55 by any one; which can be taken in the quan-

tities required to produce the desired medicinal effect of the aspirin without any objectionable effects resulting from the liquid vehicle itself, which permits instant freeing of the aspirin medicinal principle from the liquid vehicle, and which presents said medicinal principle to the action of the stomach, in already liquid form.

The preferred source from which the aspirin medicinal principle is derived is preferably ordinary commercial aspirin which, as is well known, embodies the aspirin medicinal principle in the form of a relatively stable, solid compound having an acid reaction and which is insoluble or only slightly soluble in any of the liquid vehicles ordinarily employed for medicinal purposes. As an important constituent of the liquid vehicle, I preferably employ glycerine which may be the standard commercial product containing the usual percentage of water, but in the finished product the glycerine may be and preferably is still further diluted by certain appropriate liquids, preferably of agreeable taste, as for instance, the ordinary standard syrup of cane sugar, which, if desired, may be diluted with water and alcohol and suitably flavored as with spirit of wintergreen, as in standard aromatic elixir. One purpose of such dilution is to decrease the amount of glycerine practically necessary for serving the function of vehicle, and one feature of my invention consists in the discovery that the dilution of the glycerine may be carried to a point where the amount of glycerine in ordinary doses, (equivalent to an ordinary five grain aspirin tablet), will be too small to produce the demulcent or relaxing effects which are characteristic of glycerine when used in larger doses. In producing the preferred product, the standard aromatic elixir or its equivalent has a further function which will be explained below. The precise composition of standard aromatic elixir may be found by reference to the text books, but it may be well to note here that it comprises approximately equal parts of saturated solution of cane sugar, alcohol and water with a little purified talc and a small amount of flavoring material, such as spirit of wintergreen. Other diluents may be used and in certain cases glycol may be used as a substitute for or in combination with glycerine.

The ordinary acid aspirin of commerce, 110

however, is not soluble in glycerine, and my invention contemplates the employment of an acid bicarbonate of an alkaline metal or of an alkaline earth metal, preferably an 5 easily obtainable one, as for instance potassium bicarbonate or sodium bicarbonate. The bicarbonate, preferably the bicarbonate of soda, is utilized in combination with the aspirin and the liquid vehicle, in such manner as to produce a sodium or other alkaline metal salt of aspirin. The sodium salt of aspirin is a decomposition product, the nature of which depends to some extent on the process by which it is produced, but it has 10 nearly the same medicinal properties as the acid aspirin, together with the further property of being soluble in the glycerine even though the latter be diluted for the purposes above described.

20 A desirable but more specific feature of my invention consists in combining with the aspirin solution one or more other medicinal agents, one preferably in the nature of a physic and the other preferably in the 25 nature of a tonic or stimulant; and one feature of my invention includes the investigation and discovery of desirable medicinal substances of both these classes capable of use in conjunction with the liquid vehicle, 30 the aspirin principle and with each other which are without deleterious chemical or physiological reactions either by the process of compounding or subsequent lapse of time or by stomach or other reactions after administering to the patient.

The preferred laxative is aloin, the active principle of bitter aloes, this being easily incorporated in the final product without being objectionably affected by, or itself producing objectionable effects on the other constituents.

The stimulant or tonic element is preferably elixir of lactated-pepsin, a suitable percentage of which may be added to the final 45 product and which, when employed, will constitute the mixture a mild but active stimulant, notwithstanding the fact that a limited percentage of glycerine is incorporated in the preparation.

50 While my invention is not limited to the employment of all the above constituents and while the stimulant and physic principle may be varied or omitted, if desired, nevertheless, obtaining the best balanced 55 medicinal effect of the aspirin principle in conjunction with the other medicinal agents, will depend to a considerable extent on the proportion of the various substances and the methods by which they are associated, 60 and while these may be varied within quite wide limits, the following is illustrative of a desirable way of producing a product which I have long tested and have found to result in a preparation which is superior 65 to ordinary aspirin tablets as an agency for

applying the active principle of the aspirin as a medicine, besides being in liquid form and having all of the advantages first above mentioned.

Dissolve the bicarbonate of soda in the 70 alcohol-water constituent, preferably the aromatic elixir, the quantities being proportioned so as to make a strong and preferably saturated or nearly saturated solution of the bicarbonate, then add an equal or 75 somewhat greater quantity of commercial glycerine, then gradually but not too slowly add the commercial aspirin, preferably pulverized, stirring it in thoroughly and if desired warming the mixture, but not to exceed say 50° centigrade. The amount of aspirin is by weight slightly more than twice the amount of the bicarbonate of soda. This will result in diffusing the aspirin principle 80 in soluble form throughout the liquid. If the primary bicarbonate solution is approximately saturated the resulting aspirin solution will be strong enough so that a level teaspoonful of the product will constitute a good dose, comparable to that of an ordinary aspirin tablet. Of course the solution 85 may be further diluted, if desired.

If aloin is to be used it may be mixed in the water with a small additional quantity of liquid, as for instance the aromatic elixir, 95 which may be then added to the aspirin preparation. A stimulant such as elixir of lactated-pepsin may be added to the aspirin preparation either with or without the aloin; and either before or after addition 100 of the latter.

A more specific description of desirable proportions is as follows:—

To make about a pint of the product dissolve $\frac{1}{2}$ oz. of bicarbonate of soda in say 6 105 oz. to 7 oz. of the aromatic elixir, and then add say 8 oz., that is about one-half pint of commercial glycerine. This amount of bicarbonate will take care of say 1 $\frac{1}{2}$ oz. of commercial aspirin. After the aspirin has 110 been incorporated, add enough aromatic elixir to make up the full pint and if aloin is to be employed a small quantity say about 16 grains may be mixed in a mortar with the additional aromatic elixir before adding 115 it to the liquid aspirin preparation.

While wide variations from the above are possible, excess of either bicarbonate of soda or of undissolved aspirin may be avoided by sticking fairly close to the ratio of 71% 120 aspirin to 29% bicarbonate of soda. Obviously the soluble salt of aspirin may be produced and combined with the liquid vehicle in other ways.

In the specific illustration last above 125 given it will be noted that the total weight of the product is approximately 18 oz. and that the commercial aspirin used being 1 $\frac{1}{2}$ oz., roughly stated, is somewhere around 7% of the total. The characteristic aspirin 130

groups in the aspirin salt being approximately the same in number as in the acid aspirin, it will be seen that 7% represents a close approximation of the effective aspirin strength of the product. It is obvious that a product of somewhat greater strength might be used and that it would still be useful if the aspirin percentage were reduced to 2% or even 1%.

10 In the preferred preparation where flavoring extract is employed, it is preferably the alcoholic extract, and in such case, the alcohol, though amounting only to say $\frac{1}{10}$ of a teaspoonful per dose, is in the nature of a stimulant tending to counter-
15 vail any small medicinal effects or tendencies of the half teaspoonful or less glycerine with which it is mixed.

Where a flavoring is afforded by aromatic 20 elixir containing alcohol the same thing is true. Where aloin is used with or without the alcoholic content, which would be afforded by aromatic elixir, the proportions are preferably such that the amount of mixture required for a standard dose of aspirin 25 includes only very small doses of the aloin or the alcohol or the glycerine.

I claim:—

1. A medicinal aspirin preparation comprising aspirin rendered soluble by a solution of acid bicarbonate of an alkaline metal dissolved in a liquid containing alcohol; and uniformly diffused throughout, a composite liquid vehicle comprising said first-
35 mentioned liquid mixed with and serving as a diluent for a liquid of the glycerine-glycol type.

2. A medicinal aspirin preparation made from acid aspirin rendered soluble by an 40 approximately saturated solution of acid bicarbonate of soda dissolved in aromatic elixir and mixed with a large percentage of glycerine.

3. A medicinal aspirin preparation comprising a desired weight of aspirin rendered soluble by less than half its weight of bicarbonate of soda dissolved in a medicinally harmless liquid of sufficient quantity to render the bicarbonate solution approximately 45 saturated; and uniformly diffused throughout a mixture of said liquid with an approximately similar amount of glycerine.

4. A medicinal aspirin preparation containing approximately one part each of 50 water, alcohol and syrup mixed with approximately three parts glycerine, and having an alkaline salt of aspirin dissolved therein.

5. An aspirin preparation comprising a

liquid solution containing glycerine and a diluent, and, in solution therein, a soluble aspirin salt to an amount which is by weight approximately 4% of the whole.

6. The method of making a liquid preparation of aspirin which method consists in dissolving bicarbonate of soda in a medicinally harmless solvent; mixing the resulting solution with a substantial percentage of glycerine; introducing into and rendering soluble in this mixture, the acid aspirin compound to an amount proportional to and predetermined by the amount of bicarbonate available for rendering it soluble.

7. The method of making a liquid preparation of aspirin, which method consists in rendering acid aspirin soluble by action of a solution of acid bicarbonate of an alkaline metal in the presence of glycerine serving as a solvent for the resulting soluble aspirin compound.

8. The method of making a liquid preparation of aspirin, which method consists in rendering acid aspirin soluble by action of a solution of bicarbonate of an alkaline metal in the presence of another liquid serving as a solvent for the resulting soluble aspirin compound.

9. A medicinal aspirin preparation comprising soluble aspirin, glycerine and aloin in such proportions that a standard dose of aspirin includes only very small doses of glycerine and aloin.

10. A medicinal aspirin preparation comprising soluble aspirin, glycerine, alcohol and aloin in such proportions that a standard dose of aspirin includes only very small doses of glycerine, alcohol and aloin.

11. A liquid, medicinal aspirin containing the products resulting from reaction with aspirin of carbonate of an alkaline metal or alkaline earth in solution; including the liquid of the solution and the salt of aspirin formed as a product of the reaction; all in presence of and with another medicinally unobjectionable liquid in which said salt of aspirin is dissolved.

12. A liquid medicinal aspirin containing the products resulting from action of acid aspirin with two medicinally harmless liquid mediums, in one of which the aspirin is rendered soluble with respect to the other, and in the other of which said soluble aspirin is dissolved.

Signed at New Haven, in the county of New Haven and State of Connecticut, this fifth day of February, A. D. 1921.

JACOB WERSHOW.
